(57) **CLAIM**

I claim the ornamental design for a saxophone stand, as
shown and described.

DESCRIPTION

FIG. 1 is a front and right side perspective view of a saxophone stand showing an embodiment in a closed or retracted position;

FIG. 2 is a front view of the embodiment depicted in FIG. 1;

FIG. 3 is a rear view of the embodiment depicted in FIG. 1;

FIG. 4 is a left side view of the embodiment depicted in FIG. 1, which is a mirror image of a right side view of the embodiment depicted in FIG. 1;

FIG. 5 is a top view of the embodiment depicted in FIG. 1;

FIG. 6 is a bottom view of the embodiment depicted in FIG. 1;

FIG. 7 is a front and right side perspective view of a saxophone stand showing an embodiment in an open position;

FIG. 8 is a front view of the embodiment depicted in FIG. 8;

FIG. 9 is a rear view of the embodiment depicted in FIG. 8;

FIG. 10 is a left side view of the embodiment depicted in FIG. 8, which is a mirror image of a right side view of the embodiment depicted in FIG. 8;

FIG. 11 is a top view of the embodiment depicted in FIG. 8; and,

FIG. 12 is a bottom view of the embodiment depicted in FIG. 8.

Any surfaces of the design not shown, including interior surfaces, and the subject matter of any portions subsequently shown in dashed lines form no part of the claimed invention.
